UNITED STATES PATENT OFFICE.

GEORGE F. LONG, OF ELMHURST, NEW YORK, ASSIGNOR TO GOTTFRIED PIEL, OF NEW YORK, N. Y.

FLEXIBLE SHAFTING.

1,193,277.

Specification of Letters Patent.

Patented Aug. 1, 1916.

Application filed December 12, 1913. Serial No. 806,238.

To all whom it may concern:

Be it known that I, GEORGE F. LONG, a citizen of the United States, residing at Elmhurst, in the borough of Queens of the city of New York, in the State of New York, have invented certain new and useful Improvements in Flexible Shafting, of which the following is a specification.

My invention relates to a flexible shafting comprising a plurality of stamped metal links for transmitting power and relates particularly to shafting adapted for use in connection with speedometers on automobiles or other vehicles.

One of the objects of this invention is to provide a flexible shafting composed of rigid links which may be curved both in a horizontal and a vertical plane and which is capable of transmitting power with a minimum amount of lost motion.

A further object of the invention is to provide a shaft which can be readily assembled and the links held in operative position with relation to each other without requiring any additional operation on the links after the same have been put in place.

The various other objects of the invention will be more fully set forth in the following description of one form of flexible shaft embodying my invention that is illustrated in the accompanying drawings, in which—

Figure 1 is an elevation showing several sections or links of my improved shaft connected together. Fig. 2 is a plan view of one of the shell members or links. Fig. 3 is a side elevation of one of the shell members or links. Fig. 4 is an end view of one of the shell members or links. Figs. 5 and 6 are sectional views taken respectively on the lines 6—6 and 5—5 of Fig. 2. Figs. 7 and 8 are end and side views respectively of one of the bar members or links.

The shaft is formed of a plurality of links comprising shells 1 and the bars 2 arranged longitudinally. The bar links are provided at each end with a flattened head 3 having pivot pins 4 projecting on opposite sides thereof. The heads on each bar are preferably arranged in planes approximately perpendicular to each other. The shanks 5 of the bar links are preferably rounded adjacent to the heads to form bearing surfaces 6.

The shell links comprise a substantially cylindrical central portion 7 formed of a stamped sheet metal blank by bending the

same upon itself until the adjacent edges 8 are separated by a narrow passageway 9 to receive the head 3 of the bar.

The walls of the shell are notched as at 10 to permit the pivot pins of the bar link to enter the central cavity or recess of the shell. The rear wall 11 of the shell is cut away as at 12 forming end portions 14 that are integral with the side walls of the shell and the edges of said end portions are curved to 65 form suitable bearing surfaces 15. The central part 16 of each end portion is substantially flush with the side walls, but the outer annulus or segment 17 of each end portion is flattened and is depressed adjacent to the 70 central or tubular portion of the shell. The depressed parts of each pair of end portions converge toward each other as at 18 forming a bearing for the flattened head of the bar link. The outer edges of the segments 75 17 are flared outwardly however, to permit a rocking movement of the bar link.

The central parts of the end portions are provided interiorly with grooves 20 which communicate with the interior of the shell 80 and provide bearings for the pivot pins or trunnions when the shaft is assembled.

The bar links are secured to the shell links by inserting the pivot pins or trunnions through the notches 10 and moving the same 85 forward until the pivot pins or trunnions engage in the grooves. The bar link is then swung on said pivot pins until the links are in alignment with each other. Displacement of the links by rearward movement is prevented by the shoulders or bearing surfaces 6 which are provided on the bar link coming into contact with the rounded edge 15 of the shell. When it is desired to detach the parts, the bar link is again swung at substantially right angles to the shell which causes the shoulder 6 to clear the bearing surface on the shell and thus permits the bar to be moved rearwardly until the pivot pins or trunnions are again opposite the 90 notches 10.

By means of this construction the links may be stamped from sheet metal blanks and then assembled without further operation or manipulation of any kind. The converging bearing surfaces formed by pressing end portions together prevent any lost motion when the links are twisted or rotated as when power is being transmitted. The flaring ends of the end portions however, per- 105 110 115

mit a certain amount of rocking movement of the links with respect to each other so that the shaft can be bent on a curve having a very short radius and this lateral curving of 5 the shaft can also be effected independently of any curvature of the shaft in a vertical plane.

Although I have shown only one form of mechanism embodying my invention, it is 10 obvious that various changes within the skill of the mechanic may be made therein without departing from the spirit of the invention, provided the means set forth in the following claims be employed.

15 Having thus described my invention, I claim:—

1. A flexible shaft composed of a plurality of sections, one of said sections comprising a metal shell having a longitudinal opening communicating with the interior thereof, and having relatively flat end portions integral with the side walls thereof, said flat portions being bent toward each other to form bearing surfaces and being 20 bent away from each other at their outer ends, and the other section being pivoted on the interior of the shell and provided with a flat face adapted to engage the bearing surfaces.

1. 2. A flexible shaft composed of a plurality of sections, one of said sections comprising a metal shell having a tubular central portion with its side walls spaced apart to provide a longitudinal passage communicating 25 with the interior, an extension integral with each side wall and flush therewith and provided with an interior bearing, and an annular segment integral with the side wall and surrounding each extension, said segment being depressed to form a bearing surface adjacent the central portion and flaring at its outer ends, and a separate section being pivoted to the shell section and provided with a flat head having a bearing 30 on said depressed portion of the shell.

1. 3. A flexible shaft composed of a plurality of sections, one of said sections comprising a central portion substantially circular in cross-section and having a longitudinal passageway communicating with the interior thereof, and end portions integral with the side walls each comprising a central portion having an interior bearing formed 35 therein and an annular outer portion depressed with respect to the central portion and flaring at its outer ends, and a separate section having a bearing engagement inside the shell and provided with a flat head adapted to engage the depressed portion.

1. 4. A flexible shaft composed of a plurality of sections, one of said sections consisting of a one piece hollow shell formed from a sheet metal blank having spaced side walls provided with flaring ends and a bottom 40 wall integral with the side walls interme-

diate the ends thereof, said ends comprising extensions flush with the side walls having grooves formed on the interior thereof communicating with the interior of the shell to provide a bearing spaced from the adjacent end and a portion depressed relatively to said extensions, and another section having a head provided with pivot pins adapted to be inserted transversely of the shell at about the center thereof and seating in 45 said grooves so that the head may have lateral movement with respect to the shell.

5. An element of a flexible shaft consisting of a one-piece hollow shell formed from a sheet metal blank having spaced side walls 50 provided with flaring ends and a bottom wall integral with the side walls intermediate the ends thereof, said ends comprising extensions flush with the side walls having grooves formed on the interior thereof 55 communicating with the interior of the shell to provide a bearing spaced from the adjacent end and a portion depressed relatively to said extensions.

6. As an article of manufacture, an element adapted to form part of a flexible shaft, said element comprising a one-piece channel member, an end of said member having oppositely disposed walls and each of 60 said walls having a socket formed therein, said sockets together forming a bearing spaced from the adjacent end of the member and adapted to receive a coacting element of the shaft, said channel member providing an opening leading to said bearing 65 whereby the bearing engaging portion of the coacting element may be inserted through said opening and then moved longitudinally 70 of the element onto said bearing.

7. In a device of the class described, a pair of links adapted to form a unit of a flexible shaft and comprising a one-piece sheet metal shell with its center portion substantially tubular and having similar bearings 75 adjacent opposite ends and opening into the interior thereof, and a link designed to be pivoted to either end of said shell, said link having a lateral pivot pin insertible into either of said bearings and locked from an unseating movement relative to the 80 engaged bearing when said link forms a prolongation of said shell.

8. In a device of the class described, the combination with a link having parallel end walls, of a co-acting link having a portion 85 disposed between said walls, a pivotal connection being provided between said walls and said portion, one of said links having a rib bearing on the other link and passing through the axis of said pivotal connection 90 to provide a line contact between the said walls and said portion.

9. A flexible chain including two elements pivotally linked together, the opposite ends 95 of each element being of similar configura-

- tion; one of said elements comprising a channel shaped member with the sides spaced apart to form a longitudinally extending opening communicating with the interior thereof and coextensive with the length of the channel shaped member, a bearing being formed in the member adjacent one end thereof and accessible from the interior of the member, the other element 5 comprising a body portion designed to slide along said longitudinally extending opening toward the bearing and a trunnion pin projecting from said body portion and designed to be contained within the channel member and to be seated in said bearing from the interior of the channel member and a stop on said other element for preventing the pin from moving from said bearing while the elements are alined and designed 15 to permit the unseating of the pin when the elements are angularly disposed relative to each other.
10. As an article of manufacture, an element adapted to form part of a flexible shaft, said element comprising a one-piece sheet metal shell including side walls curved to form a substantially cylindrical central portion with adjacent longitudinal edges separated to form a narrow passageway, one 20 of said edges being notched intermediate its length to increase the width of the passageway at this point, and substantially parallel end portions extending beyond the central cylindrical portion at one end thereof, the central portion of each end portion being substantially flush with the side walls and the outer portion of each of said end portions being flat, the central parts of each 25 end portion being provided with grooves designed to provide bearings for a coacting element of the flexible chain, the distance between the bottoms of said grooves being substantially equal to the width of said passageway at the notched edge of the side wall.
- 30 11. As an article of manufacture, an element adapted to form part of a flexible shaft, said element comprising a one-piece sheet metal shell including side walls curved to form a substantially cylindrical central portion with adjacent longitudinal edges separated to form a narrow passageway, and substantially parallel end portions extending beyond the central cylindrical portion at one end thereof, the central portion of each end portion being substantially flush with the side walls and the outer portion of each of said end portions being flat, the central portions of each end portion being provided with grooves designed to provide 35 bearings for a coacting element of the flexible chain, said end portions diverging from the central portion of the shell and having rounded edges designed to engage the coacting element at widely spaced apart points should the coacting element and the shell tend to telescope each other when forming parts of the flexible shaft.
- 40 12. As an article of manufacture, an element adapted to form part of a flexible shaft, said element comprising a one-piece sheet metal shell including side walls curved to form a substantially cylindrical central portion with adjacent longitudinal edges separated to form a narrow passageway, and substantially parallel end portions extending beyond the central cylindrical portion at one end thereof, the central portion of each end portion being substantially flush with the side walls and the outer portion of each of said end portions being flat, the central portions of each end portion being provided with grooves designed to provide 45 bearings for a coacting element of the flexible chain, said end portions diverging from the central portion of the shell and having rounded edges designed to engage the coacting element at widely spaced apart points should the coacting element and the shell tend to telescope each other when forming parts of the flexible shaft.

This specification signed and witnessed this 11th day of December, 1913.

GEORGE F. LONG.
